FOREIGN PATENT DOCUMENTS

WO DM-075166 1/2011

Primary Examiner — Rhea Shields

(74) Attorney, Agent, or Firm — Adibi IP Group, PC;
Amir V. Adibi; Andrew C. Palmer(57) **CLAIM**

The ornamental design for a half-dozen pastry container, as shown and described.

DESCRIPTION

FIG. 1 is a front perspective view of a half-dozen pastry container showing my new design.

FIG. 2 is a top view showing my new design.

FIG. 3 is a bottom view thereof.

FIG. 4 is a left side view thereof; the right side view (not shown) being a mirror image thereof.

FIG. 5 is a front view thereof; the back view (not shown) being a mirror image thereof.

FIG. 6 is a front perspective view thereof; showing the half-dozen pastry container in an environment; and,

FIG. 7 is an exploded view of the half-dozen pastry container showing my new design.

In FIG. 6, the broken lines are for the purpose of illustrating the environment only and form no part of the claimed design.

1 Claim, 7 Drawing Sheets
